UNITED STATES PATENT OFFICE.

MARSHALL BROWNE HERN, OF BIRMINGHAM, ENGLAND, ASSIGNOR TO JOHN HERN AND MARIA HERN, OF MANCHESTER, ENGLAND.

TOBACCO-PIPE.

SPECIFICATION forming part of Letters Patent No. 708,142, dated September 2, 1902.
Application filed March 28, 1902. Serial No. 100,432. (No model.)

To all whom it may concern:

Be it known that I, MARSHALL BROWNE HERN, a subject of the King of Great Britain and Ireland, and a resident of Arcade Chambers, 89 Corporation street, in the city of Birmingham, England, have invented certain new and useful Improvements Relating to Tobacco-Pipes, (for which I have filed an application in Great Britain, No. 17,527, bearing date September 2, 1901,) of which the following is a specification.

This invention consists of improvements relating to tobacco-pipes, whereby I am enabled in a simple and convenient manner to protect the tobacco in the pipe-bowl from contact with the moisture which accumulates in the pipe-stem or smoke-passages, and thus to effect an economy in the amount of tobacco consumed and also to provide for the cooling of the smoke and for the ready and effectual cleaning of the whole interior of the pipe.

Referring to the accompanying sheet of explanatory drawings, Figure 1 is an external elevation, and Fig. 2 a part-sectional elevation, of a pipe constructed in accordance with my invention. Fig. 3 is a plan showing the bowl end of the pipe, but with its inner and cap part removed. Fig. 4 is an elevation of the said inner and cap part of the bowl.

The same reference-letters in the different views indicate the same parts.

The bowl consists of two main parts, an inner and cap part A and a top body part B, which is formed with the usual stem C. The mouthpiece D is detachably connected with the outer end of the said stem in any ordinary manner.

The inner and cap part A is screw-threaded, as shown at Fig. 4, and a corresponding thread is formed within the body part B of the bowl. The part A can thus be readily fitted within or detached from the part B. The part A is provided with a lining, as F, of meerschaum or other material, to protect it from the heat generated by the burning of the tobacco placed within it.

The central aperture within the bowl part B is of such depth that when the part A is secured within the said aperture until its annular shoulder a is drawn tightly against the top of the part B a sump or moisture-collect-

ing chamber F is provided between the connected parts. I preferably insert a piece, as F', of sponge or other absorbent material, in the bottom of the sump. I also preferably place a thin metal washer, as A', beneath the annular shoulder a to prevent its adhesion to the part B. The interior of the bowl part A communicates with the aforesaid sump or collecting-chamber F by means of the passage a', and the said chamber is also connected by means of the passage b with an annular groove b', formed around the top of the body part B of the bowl. The said groove also communicates by way of the passage b' 65 with the central aperture c in the stem C.

The course taken by the smoke under the drawing action of the person using the pipe is as follows: From the interior of the inner bowl part A the smoke passes through the passage a' to the sump F and from thence by the passage b to the annular groove b'. After traveling around one semicircular portion of the said groove in either direction the smoke descends through the passage b' to the central aperture c in the stem C, and from thence it passes out by way of the central passage formed through the mouthpiece D.

With a pipe constructed as aforesaid the tobacco is protected from the moisture which accumulates during smoking, while the smoke is cooled before entering the mouth of the smoker through having to take a circuitous course through passages which, with the whole interior of the pipe, can be very readily and effectually cleaned.

Having thus described my invention, what I claim, and desire to secure by Letters Patent, is—

1. In a tobacco-pipe, the combination consisting of an outer bowl part B having an annular groove b' on its upper end and diametrically-opposed passages b b' through its body respectively putting the said annular groove into communication with a sump F at the bottom of B and with the aperture c in the pipe-stem C, and an inner bowl part A detachably connected with B and communicating with the said sump F in the same but preventing the smoke from flowing up around its exterior and thence directly to the said passage b', substantially as described.

2. In a tobacco-pipe, the combination consisting of an outer bowl part B having an annular groove b' in its upper end and diametrically-opposed passages $b' b^2$ through its body 5 respectively putting the said annular groove into communication with a sump F at the bottom of B with the aperture c in the pipe-stem C, an inner bowl part A detachably connected with B and communicating with the sump F 10 in the same but preventing the smoke from flowing up around its exterior and thence di-

rectly to the said passage b^2 , and a metal washer A' disposed between the said parts A and B to prevent their adhesion, substantially as described.

In witness whereof I have hereunto set my hand in presence of two witnesses. 15

MARSHALL BROWNE HERN.
